UNITED STATES PATENT OFFICE.

WILLIAM E. FOREST, OF LOS ANGELES, CALIFORNIA.

OIL-STORAGE CAN.

SPECIFICATION forming part of Letters Patent No. 633,441, dated September 19, 1899.

Application filed January 30, 1899. Serial No. 703,778. (No model.)

To all whom it may concern:

Be it known that I, WILLIAM E. FOREST, a citizen of the United States, residing in the city of Los Angeles, in the county of Los Angeles 5 and State of California, have invented certain new and useful Improvements in Oil-Storage Cans; and I do hereby declare the following to be a full, clear, and exact description of the invention, such as will enable others skilled in the art to which it appertains to make and use the same, reference being had to the accompanying drawings, and to letters and numerals of reference marked thereon, which form a part of this specification.

15 This invention relates to that class of oil-storage cans shown in my prior application filed September 1, 1898, Serial No. 691,486, the objects of the present invention being to secure a more convenient support for the 20 storage-can and one which can be more cheaply and easily constructed, to thus reduce the cost of manufacture, to provide a support which permits ready access to all parts and one which presents very little opportunity for the lodgment of dirt or foreign 25 matter and will not become unpleasantly impregnated with oil, to thus obtain increased cleanliness, and to secure other advantages and results, some of which may be hereinafter referred to in connection with the description 30 of the working parts.

The invention consists in the improved support or stand for oil-storage cans and in the arrangements and combinations of parts of 35 the same, all substantially as will be herein-after set forth and finally embraced in the clauses of the claim.

Referring to the accompanying drawings, in which like letters and numerals of reference 40 indicate corresponding parts in each of the several views, Figure 1 is a side elevation of the support or stand with a storage-can in position thereon. Fig. 2 is a perspective view of the support with the oil-can removed, and 45 Fig. 3 shows a certain base-brace which forms a part of the stand.

In said drawings, *a* indicates the storage can or receptacle, and *b* the support or stand for holding said can. Said can is substantially the same as set forth in my prior application above referred to and comprises a cylindrical body *c*, provided at the upper side

with a filling-mouth *d* and bail *e* and at the lower side with legs *f* to hold the can upright when taken out of the stand or support. At the 55 front of the can are a spout *g* and a vent-pipe *h*, extending from the nozzle of said spout to the filling-mouth *d*, where it communicates with the interior of the can, and at the opposite lateral ends of the can are trunnions *i*, 60 eccentrically disposed with reference to the center axis of the can and parallel thereto. All said parts being the same as fully set forth and described in my previous application, further description here is deemed un- 65 necessary.

The support or stand *b* I form of wire, preferably of iron wire, of a size sufficient to give the necessary strength and rigidity. It will be obvious that a wire stand possesses great 70 advantages, such as allowing the sides to be open, permitting access to all parts of the can, affording no place for the lodgment of dirt or spilled oil, securing great lightness of weight, &c.

In my preferred construction I form the support of two pieces of wire, a body part *j* and a base-brace *k*, said parts being joined together by a winding of light wire, as at *l*. Said body part *j* comprises two parallel trapezoidal 80 side frames *m m* at their upper rear corners, connected by a horizontal bar *n*, all in one integral piece of wire bent into the shape described. It is necessary in my construction that the said side frames *m m* be parallel or 85 substantially parallel, as described, since my rotating oil-storage can has its opposite lateral ends vertical and parallel and could not be seated between converging side frames so as to rotate therebetween.

The trapezoidal shape of the side frames *m m*, besides presenting a neat appearance, is especially adapted to my flat-ended can in that said side frames project forwardly to protect the lateral ends of the can from contact or 95 blows. At the same time there is no waste of wire or material and a flat vertical back is secured, whereby the stand may be hung against the wall and be as firm in that position as when standing on the floor. Again, I 100 am thus enabled to secure vertical loops or bearings *o*, from which the trunnions of the oil-can are not easily displaced and a maximum degree of security is provided. Each of

said trapezoidal side frames occupies a vertical position, with the lower side 2 of the trapezoid normally horizontal, the two unequal parallel sides 3 and 4 being approximately 5 vertical, with the shorter at the front of the stand. The portion of wire forming the upper side 5 of the trapezoid therefore slopes forwardly downward from the horizontal bar 70 n , before described, all as will be clearly understood by reference to Fig. 2 of the drawings.

The lower horizontal portions 2 of the side frames m are connected by a base-brace k , shown separate from the other parts in Fig. 3. 15 This brace k is substantially rectangular in general outline, and its two lateral sides are arranged contiguous to the lower bars of the vertical side frames m of the body portion and bound thereto by a spiral winding of 20 lighter wire l . The rear side of the base-brace k lies vertically beneath the horizontal bar n , and the front edge is bent or curved inward, as at q , from the vertical plane of the front ends of the side frames m , so as to allow 25 the lamp to be held more directly beneath the spout of the can in filling. The base-brace k thus lies in a horizontal position upon the floor where the stand or support is stood, and its opposite lateral sides are in longitudinal contact with the bottoms of the side frames m and firmly secured thereto for 30 their entire length. This provides a rigid base which will not twist or rack out of shape and gives to the stand firmness and rigidity 35 where most needed—viz., below the center of gravity of the oil-can—so that the stand will not twist or shake under the weight of the filled and heavy can. The upper part of the frame does not need so rigid a connection and 40 the single horizontal wire n suffices.

The base-brace k can be made separate from the body part of the stand and be readily connected thereto in assembling. This enables the stand to be made in two separate pieces, 45 neither of which is complicated or difficult to manufacture. On the contrary, each piece has only a few plain simple bends, mostly at right angles, which are readily made.

The ends k' of the base-brace are disposed at one side of the stand, where they 50 closely approach each other, the extremities being bent inward at right angles to project through the turns of the wire l and engage the same to prevent movement. By this arrangement I avoid soldering or otherwise joining the said ends to each other.

It is obvious that instead of joining the body portion j and base-brace k by winding, as described, I may effect such union by soldering, riveting, or any other method common to the wire-workers art. Furthermore, the exact points at which bending takes place or ends are secured may be varied without departing from the spirit or scope of the invention.

At suitable points on the upper forwardly inclined portions 5 of the side frames of the

support, preferably near the middle, I form downward bends or loops o , providing seats for the end trunnions of the oil-can. Said can is dropped into place from the top, the cylindrical body lying endwise between the opposite vertical side frames m of the stand, with the horizontally-projecting trunnions resting at the bottoms of the loops or bends 75 o . The can is thus free to be oscillated in said bearings to cause an outflow from the spout, as will be understood, while because of the curve in the front of the base-brace the lamp can be held upright beneath said 80 spout.

It is evident that instead of standing my support upon a table-shelf or the like it may be hung upon a wall by simply hooking the rear horizontal bar n over a nail, hook, or the like. I prefer to form in said horizontal bar a central upward bend or curve p , adapted to retain the support in central position more securely when thus hung upon a wall or similar support. 90

By my construction it is evident that the front of the stand is entirely open and unobstructed by any cross-bars or projections above the level of the base. This enables the oil-can to be slid into place from the front 95 without lifting it up over an obstacle and then dropping it down again into its seat, as would be necessary if only the top were open. Much labor is thus saved, and, moreover, perfectly free access is permitted to the can in 100 filling lamps, &c.

Having thus described the invention, what I claim as new is—

1. The combination with a pivotal storage-can, of a wire supporting-stand comprising a 105 body portion having vertical side frames arranged substantially parallel and connected at their rear top parts, and a horizontal base-brace, of substantially the same dimensions and outline as the bottom of the stand, connecting the said side frames, substantially as set forth.

2. The herein-described support for pivotal oil-cans, comprising trapezoidal side frames of wire vertically disposed and connected by a wire brace substantially rectangular in form and having two opposite sides substantially equal in length to the side frames from front to back and secured thereto, substantially as set forth. 115

3. The herein-described supporting-stand for pivotal storage-cans, comprising vertical side frames formed of wire and connected by a horizontal bar, and a wire brace substantially rectangular in form and having two opposite sides secured, respectively, to the corresponding lower bars of the side frames and being substantially equal thereto in width from front to back and lying in the plane of the base of the stand, substantially as set 125 forth.

4. The combination with the pivoted oil-can, of a wire support in the shape of a truncated square prism, the lower in height of the

two rectangular faces being left open at its upper side and having the wire forming the lower side bent or curved inward toward the opposite face, said support having its upright edges vertical, its lower horizontal edges in the plane of the base and its upper rear edges bent to hook over a nail or the like, and having loops or bends in the upper inclined side edges for the pivots of the oil-can, substantially as set forth.

5. In a wire support for a pivotal oil-can, the combination of trapezoidal side frames having their inclined sides uppermost and loops or bends formed therein for the pivots 15 of the can, means for connecting the upper

parts of said side frames, and a base-brace for joining the lower parts, said base-brace consisting of a substantially rectangular wire piece having its front bent inward and its sides substantially equal in length to the bottoms of the side frames, and secured thereto by a winding of wire, substantially as set forth.

20 In testimony that I claim the foregoing I have hereunto set my hand this 21st day of January, 1899.
